FINISHING MACHINE FOR ELONGATED
TAPERED ARTICLES

Donald M. Kitterman, Kansas City, Kans.

Application April 25, 1949, Serial No. 89,403

8 Claims. (Cl. 51—88)

1

This invention relates to apparatus for finishing elongated articles through a grinding operation along the entire length thereof, the primary object being to provide a pair of opposed grinding discs movable toward and away from each other as the same rotate and as the article to be ground is directed therebetween, to the end that the amount of material removed by the discs from the article being ground, can be varied as desired along the length of such article.

It is the most important object of the present invention to provide a grinder for tapering an elongated, initially cylindrical article through the medium of a pair of rotatable grinding discs, movable toward and from each other and normally held biased together and in grinding relationship to the article, there being a cam member shaped in conformity with the desired shape of the finished article movable between the mounting means for the disc simultaneously with the article being ground to effect to increase the distance between the rotating disc.

Another important object of the present invention is to provide a grinding device as above set forth, having as a part thereof structure for continually rotating the article being ground between the rotating discs as such article is moved along a rectilinear path between such discs.

A further object of the present invention is to provide a machine for tapering elongated articles having structure capable of engaging the article being ground to rotate the same and provided with novel means for permitting longitudinal movement of the elongated article as the same is being rotated.

Another object of the present invention is to provide means interconnecting the supports for the rotating grinders operable to effect uniform reciprocable movement of the rotating discs toward and away from each other as the machine is placed in operation.

Other more minor, yet important objects, will be made clear or become apparent as the following specification progresses, reference being had to the accompanying drawings, wherein:

Figure 1 is a fragmentary, side elevational view of a finishing machine for elongated tapered articles made in accordance with my present invention, parts being broken away to reveal details of construction.

Fig. 1a is a side elevational view showing a continuation of the machine illustrated in Fig. 1.

Fig. 2 is a top plan view of a portion of the machine.

Fig. 3 is a cross-sectional view taken on line III—III of Fig. 2.

2

Fig. 4 is a vertical transverse, cross-sectional view taken on line IV—IV of Fig. 3, looking in the direction of the arrows.

Fig. 5 is a vertical, transverse, cross-sectional view taken on irregular line V—V of Fig. 2.

Fig. 6 is a fragmentary, side elevational view.

Fig. 7 is an enlarged, detailed, cross-sectional view taken on line VII—VII of Fig. 2.

Fig. 8 is a transverse, cross-sectional view taken on line VIII—VIII of Fig. 7, looking in the direction of the arrows; and

Fig. 9 is a fragmentary, stretched-out perspective view showing a portion of the article receiving and holding means forming a part of the machine.

A pair of parallel, elongated, horizontally disposed beams 10 and 12 are mounted at the ends thereof on a pair of supports 14 and 16 respectively.

Beams 10 and 12 have rigidly secured thereto and intermediate the ends thereof, a pair of spaced-apart, parallel cross bars 18 and 20.

A plurality of short blocks 22 underlying the beams 10 and 12, are releasably secured to the cross bars 18 and 20 in any suitable manner to hold the latter rigid to the beams 10 and 12.

Cross bars 18 and 20 support a pair of horizontal, rectangular plates 24 and 26 that are spaced apart at their innermost proximal edges and secured directly to the cross bars 18 and 20 in any suitable manner not shown. Accordingly, the plate 24 is disposed directly above the beam 10 with its longitudinal axis parallel with beam 10 and the plate 26 is disposed above beam 12 in the same manner.

Each plate 24 and 26 is provided with a transverse, relatively wide cavity designated by the numerals 28 and 30 respectively, having one longitudinal edge thereof under-cut in the manner illustrated in Figs. 3 and 6.

A pair of blocks 32 and 34, each being dovetailed in cross-section as shown in Figs. 3 and 6, are reciprocably mounted within the cavities 28 and 30 respectively for movement toward and away from each other in aligned paths of travel traversing the longitudinal axes of beams 10 and 12. One longitudinal edge of the blocks 32 and 34 is slidably received by the under-cut portion of its corresponding cavity 28 or 30. Strips 36 and 38 within cavities 28 and 30 respectively, are removably secured to the corresponding plate 24 or 26 through the medium of screws or the like 40, for locking the reciprocable blocks 32 and 34 in place.

Each of the blocks 32 and 34 is provided with a longitudinal open top groove 42 that is covered

by a plate 44 and 46 joined directly to blocks 32 and 34 respectively in any suitable manner. The grooves 42 each receive an elongated bar 48 having a pin 50 on the innermost end thereof that extends downwardly into cavities 28 and 30 as the case may be adjacent the inner end of the corresponding block 32 and 34.

The pins 50 each swingably receive a short link 52 that underlies the bar 48. A shaft 54 journaled in link 52 and parallel with pin 50 extends downwardly adjacent the innermost end of the corresponding plate 24 or 26 and has a roller 56 mounted thereon for free rotation. The upper and lowermost ends of the shaft 54 project above link 52 and below roller 56 to receive the bifurcated end of an elongated arm 58. That end of the arm 58 opposite to roller 56, receives a vertical pin 60 secured by set screw 61 at its uppermost end to a panel 62 that has a portion thereof disposed above the cross bar 20 midway between the ends of the latter.

The arm 58 has a gear 64 rigidly secured to its lowermost edge and mounted on the pin 60 directly above a member 66 that receives the lowermost end of the pin 60. Member 66 is secured to bar 20 and to a block 68 overlying and joining the bar 20. Block 68 is perforated as at 70 to clear a template or cam member 72 as will hereinafter appear. The panel 62 is likewise joined to the member 68.

Accordingly, each block 32 and 34 carries therewith for reciprocable movement, a bar 48 having a roller 56 thereon. Each roller 56 is joined through a shaft 54 with an arm 58. The two arms 58 are connected with panel 62 and with member 68 through a pin 60 and accordingly, there is provided a pair of gears 64 that are always intermeshed as illustrated in Fig. 2 of the drawings. Each of the blocks 48 is provided with an adjusting screw 74 having an operating knob 76 on the outermost end thereof for varying the distance between the two rollers 56 at any given point along the reciprocable paths of movement of the blocks 32 and 34.

A set screw 78 in plate 44 or 46, as the case may be, releasably locks the block 48 in the adjusted position. It is thus seen that movement of either of the blocks 32 or 34 will transmit movement to the other block through the gears 64, all to the end that reciprocable movement of blocks 32 and 34, and all of the parts carried thereby, is maintained uniform.

A pair of L-shaped brackets 80 carried by the outermost edges of each of the plates 24 and 26, each receive an adjustable screw 82 that in turn receives one end of a spring 84, the opposite end of each of the springs 84 extending into a cavity 86 formed in the outermost ends of the reciprocable blocks 32 and 34. Thus, blocks 32 and 34, as well as their rollers 56, are yieldably held at the innermost ends of their paths of travel by the four springs 84.

A pair of electric motors 88 and 90 are mounted directly upon the uppermost faces of the plates 44 and 46 with their drive shafts parallel, and perpendicular to the paths of travel of the plates 44 and 46 and their respective underlying blocks 32 and 34. Each of such drive shafts carries a grinder disc 92.

Referring now to Figs. 1 and 1a of the drawings, the beams 10 and 12 slidably receive a carriage 94, movable toward and away from the supporting member 14 and accordingly toward and away from the grinder discs 92. Rectilinear movement is imparted to the carriage 94 in one

direction through the medium of an electric motor 96 that drives, through suitable reduction gearing, a gear 98 that meshes with an elongated rack 102 extending parallel with the beams 10 and 12 and thereabove, from the carriage 94 toward the grinding assembly including discs 92. The cam member 72 referred to above, comprises an elongated tapered rod having its base end secured directly to that end of the rack member

10 102 opposite to the carriage 94.

Gear 98 is mounted on a spring-loaded lever 100 normally held in place with gear 98 meshing with rack 102 by a spring-loaded trigger 104.

An ear 106 on the rack 102, intermediate the ends thereof, serves to trip the trigger 104 and thereby to release the gear 98 when the carriage 94 reaches that end of its path of travel remote from the support 14.

A plurality of up-standing supporting members 107 carried by the beams 10 and 12, receive bearings 108 at the uppermost ends thereof that in turn journal an elongated tube 110 directly above and parallel with the longitudinal axis of template 72. One end of the tube 110 has 25 an enlarged head 112 thereon provided with a frusto-conical cavity 114 for receiving a complementary head 116 of a relatively short tube 118 provided with a polygonal bore 120.

Interlocking ears 122 and slots 124 on heads 30 116 and 112 respectively, prevent relative rotation between the tubular members 118 and 110 when the cavity 114 in head 112 is received by the head 116.

An elongated plunger 126 rotatably secured at 35 one end thereof to the carriage 94, is also polygonal in cross-section and adapted to be received by the bore 120 as well as the opening through the tube 110.

An ear 128 is formed on that end of the plunger 40 126 opposite to carriage 94. A follower 130, slidably mounted on a rod 132 and on the plunger 126, rotatably supports the latter.

The rod 132 is secured to the proximal support 45 107 at one end thereof and is slidably received by the carriage 94 adjacent its opposite end. Movement of the carriage 94 and its component parts including rack 102, follower 130 and plunger 126 in a direction toward the support 14, is through the medium of an hydraulic system including a cylinder 134 disposed between the beams 10 and 12 adjacent the support 16 and to one side of the frame pieces 18 and 20 opposite to the carriage 94.

Hydraulic cylinder 134 has an elongated 55 plunger 136 extending therefrom parallel with and between the beams 10 and 12 and joining with the carriage 94 at its outermost free end, as illustrated in Fig. 1. A roller 138 supports the rack 102 throughout its reciprocable movement.

That end of the elongated tube 110 opposite to the head 112 thereof, passes through a hollow body 140 that is in turn mounted on a bracket 142 carried by the cross-bar 18, the bracket 142 being perforated as at 144 to clear the template 72. Body 140 has a pair of bearings 146 for rotatably receiving the proximal end of tube 110 and a collar 148 circumscribes a portion of the tube 110 within the body 140 and is slidably mounted thereon.

One end of the collar 148 has a frusto-conical cavity 150 that bears against a plurality of sharpened discs 152 passing through slots 154 formed in the tube 110. A spring 156, coiled 75 about the tube 110, yieldably holds the collar 148

bearing against the discs 152. The shafts that journal each of the discs 152 traverse the slots 154 as shown in Fig. 8 and have their ends seated in outwardly facing cavities, there being such a cavity on each side of each slot 154 respectively.

That end of the tube 110 that projects slightly beyond the body 140 is in direct alignment with the space between the rotating grinding discs 92 and with a tubular guide 158 on the opposite side of grinding discs 92.

Guide 158 is in turn aligned with a tube 160 supported by a bracket 162 extending inwardly from the crossbar 20. A support 164 is mounted directly below the grinding discs 92 and is vertically adjusted through the medium of a bolt 166 locked in place by set screw 168. The uppermost end of the support 164 is angled toward the proximal end of tube 110 as at 170.

Continual rotation of the elongated tube 110 is accomplished through use of an electric motor 172 having connection through belt 174 with a sheave 176 mounted directly on the tube 110 adjacent the body 140.

In operation, an elongated member such as a glass fishing rod (not shown) that is originally cylindrical in cross section and that is to be tapered in conformity with the shape of the template 72, is threaded into the tube 110 when the carriage 94 is at that end of its path of travel adjacent the support 14 and when the plunger 126 is thus retracted from the tube 110. Movement of the carriage 94 toward the brackets 107, will move the plunger 126 into the tube 110 and force the rod longitudinally through the tube 110 until it comes into contact with the discs 152.

The rod will force the discs 152 outwardly against the action of spring 156 and the discs 152 will bite into the rod and prevent rotation of the latter relative to the tube 110. Tube 110 is constantly rotating through energization of the motor 172 and since the collar 148, together with the discs 152 rotate therewith, the rod will accordingly be rotated as the same is pushed through the tube 110 along a straight path of travel by the plunger 126.

From the tube 110, the rod will be directed to inclined face 170 of support 164 and be thereupon directed into the guide 158 and the relatively short tube 160. While the carriage 94 and its plunger 126 drive the rod in the manner just mentioned, carriage 94 will also drive the template 72 through the opening 144 and between the rollers 56. Such movement of cam member 72 between rollers 56, will progressively increase the distance between the two rotating grinder discs 92 because movement of the rollers 56 away from each other, will move blocks 48 apart to in turn move the blocks 32 and 34 and plates 44 and 46 outwardly. The outward movement of the grinders 92 will be uniform because of the provision of gears 64 as above explained.

Motor 96 operates continually but as soon as the ear 106 releases gear 98, movement of carriage 94 will cease and at this point, the rod will have passed through the grinding elements 92 and be ready for removal from the tube section 160. The operator thereupon, operates the hydraulic system including cylinder 134, to force plunger 136 toward the support 14 and to thereby return the carriage 94 to its starting position. Oftentimes it may be desirable or necessary to regrind a tapered rod and when such operation takes place, the discs 152 will be incapable of holding such tapered rod against rotation rela-

tive to the tube 110. The base end of the tapered rod to be re-ground, is slotted for receiving ear 128 of the plunger 126. Rotative movement is imparted to such tapered rod from the rotating tube 110 through the heads 112 and 116, and the rotatable plunger 126.

It is seen from the foregoing that rods are tapered in conformity with the cam member 72 through use of the rotating grinding wheels 92 that are held biased against rod through the medium of springs 84. As the rod is forced through the tube 110 along the rectilinear path of travel, rotative movement is imparted to the rod by the rotating tube 110. Because of a uniform speed of movement of the rod through the tube 110, through a constant uniform speed of rotation of the cutting wheels 92, and through progressive and uniform outward movement of the rollers 56, the finished rod will have a longitudinal taper and the diameter thereof will progressively increase as the base end thereof is approached.

Having thus described my invention, what I claim as new and desire to secure by Letters Patent is:

1. In a finishing machine for elongated articles, a pair of opposed, rotatable grinding wheels mounted for movement toward and away from each other; structure for continuously moving the article to be finished in one direction on its longitudinal axis between said grinding wheels and with respect thereto; means for yieldably holding the grinding wheels biased against said article as the same is being moved; means for simultaneously rotating the article on said axis as the same is moved; and means for progressively increasing the distance between the grinding wheels as the article is moved therebetween.

2. In a finishing machine for elongated articles, a pair of opposed, rotatable grinding wheels mounted for reciprocation toward and away from each other; a support for each grinding wheel respectively; structure for holding the article to be finished between said grinding wheels; apparatus for imparting relative movement to the article and the grinding wheels with respect to the longitudinal axis of the article; spring means for yieldably holding the grinding wheels biased against said article; template means for progressively moving the grinding wheels away from each other against said means as said apparatus operates; and mechanism operably interconnecting said supports for moving the latter in response to operation of said spring means and said template means to synchronize the reciprocation of the grinding wheels.

3. In a finishing machine for elongated articles, structure for continuously moving an article to be finished on its longitudinal axis along a rectilinear path of travel and simultaneously rotating the article on said axis, said structure comprising a rotatable tube adapted to receive said article; a plunger for forcing the article through the tube; and means for connecting the article with the tube for rotation therewith as the article is moved through the tube.

4. In a finishing machine for elongated articles, structure for simultaneously moving an article to be finished on its longitudinal axis along a rectilinear path of travel and rotating the article on said axis, said structure comprising a rotatable tube adapted to receive said article; a plunger for forcing the article through the tube; and means for connecting the article with the tube for rotation therewith, said means including parts for

joining the plunger and the article and elements for joining the plunger and the tube.

5. In a finishing machine for elongated articles, structure for simultaneously moving an article to be finished on its longitudinal axis along a rectilinear path of travel and rotating the article on said axis, said structure comprising a rotatable tube adapted to receive said article; a plunger for forcing the article through the tube; and means for connecting the article with the tube for rotation therewith, said means including at least one member rotatably carried by the tube and engagable with said article, said member being disposed for engagement by the article for rotation thereby as the same is forced through the tube.

6. In a finishing machine of the kind described, a pair of members movable toward and away from each other; means for yieldably holding the members biased together; and mechanism to equalize outward movement of the members as an article is forced therebetween to force the same apart against the actions of said means, said mechanism including a pair of intermeshing gears and an arm for each gear respectively and mounted for swinging movement thereby, each arm being operably connected with a corresponding member.

7. In a grinding machine, a pair of spaced supports; a block for each support respectively and carried thereby for reciprocable movement of the blocks toward and away from each other; a grind-

ing wheel carried by each block respectively; yieldable means on each support respectively and engageable with the blocks thereof for holding the blocks biased toward each other; and a roller attached to each block respectively and adapted to receive a movable template therebetween to separate the blocks against the action of said yieldable means to move the grinding wheels apart.

8. In a grinding machine as set forth in claim 7 wherein each block is provided with a roller supporting bar, the bars being shiftable toward and away from each other with respect to their blocks, and wherein means is provided for each bar respectively for holding the same in selected positions relative to the corresponding blocks.
